(57) **CLAIM**

The ornamental design for a loudspeaker, as shown and described.

DESCRIPTION

1. Loudspeaker
- 1.1 : Perspective
- 1.2 : Perspective
- 1.3 : Front
- 1.4 : Back
- 1.5 : Left
- 1.6 : Right
- 1.7 : Top
- 1.8 : Bottom

The design shows a loudspeaker that is shaped like a strip, the essential characteristics of the design are featured in its shape; the purpose of the claimed design is used to play sound; perspective view shows the best features of the design points; the broken lines shown in the drawings are included for the purpose of illustrating portions of the loudspeaker that form no part of the claimed design.
